UNITED STATES PATENT OFFICE.

RICHARD SMITH, OF SHERBROOKE, QUEBEC, CANADA, ASSIGNOR OF ONE-HALF TO THE FALL MOUNTAIN PAPER COMPANY, OF BELLOW FALLS, VERMONT.

AUTOMATIC GUIDE-ROLL ATTACHMENT.

SPECIFICATION forming part of Letters Patent No. 362,674, dated May 10, 1887.

Application filed December 6, 1886. Serial No. 220,866. (No model.)

To all whom it may concern:

Be it known that I, RICHARD SMITH, a citizen of Canada, residing at Sherbrooke, in the county of Sherbrooke and Province of Quebec, 5 Canada, have invented certain new and useful Improvements in Automatic Guide-Roll Attachments; and I do hereby declare the following to be a full, clear, and exact description of the invention, such as will enable others skilled in 10 the art to which it appertains to make and use the same, reference being had to the accompanying drawings, and to letters or figures of reference marked thereon, which form a part of this specification.

15 This invention relates to "guides," so called, by which the direction and path of travel of a continuously-traveling endless band or apron are regulated and controlled. This guide belongs to that class termed "automatic," since 20 any great deviation in the band from its proper path of travel causes activity in its mechanism to oppositely shift the position of the guide-roll, and thus the band is caused to return and resume its normal path. Hence it 25 will be seen that the band controls its own path of travel.

The essential feature in this automatic guide consists in journaling the guide-roll at one end upon a carriage mounted upon a sleeve-shaft 30 which is disposed above a screw-shaft. Rotations of the guide-roll communicate continuous rocking motion to a shaft furnished with pawls, while the activity of the latter is dependent upon the position of the continuously- 35 traveling endless band. The lower part of the carriage contains a nut, which engages the screw-shaft, while a toothed wheel is affixed to one end of the latter. Thus rotation of this toothed wheel effected by the action of the 40 pawls causes the nut to travel to and fro upon the screw-shaft, shifts the carriage, and thereby adjusts and maintains the guide-roll in the position required to control the direction and path of movement of the endless band or apron 45 to prevent it diverging therefrom.

This invention may be considered an improvement upon that shown and described in Letters Patent of the United States No.

339,703, and issued to myself on the 13th day of April, 1886.

50 The drawings accompanying this specification represent, in Figure 1, a side elevation of an automatic guide apparatus embodying my invention. Fig. 2 is an end elevation of the same. Fig. 3 is a vertical transverse section 55 on line *x x* in Fig. 1. Fig. 4 is a part plan view of the stop-lever mechanism.

In the above drawings I have represented a stand, A, adapted to be bolted to the frame of a paper-making or other machine at a point 60 where the guide-roll B of the endless band is to be located. This stand or bracket A supports one end of the guide-roll with its controlling and actuating mechanism, to be hereinafter described, while the opposite end of 65 said roll is journaled in a fixed bracket at the rear or back side of the machine-frame. (Not shown.) This guide-roll is, as usual, mounted transversely of the machine, and likewise of the path of travel of the endless band, which 70 is shown at C.

The front stand, A, is formed with two vertical posts, *a a'*, which furnish bearings for a stationary tubular shaft, D, horizontally disposed and vertically aligned above a rotary 75 screw-threaded shaft, E, to which is affixed a toothed wheel, F. This latter may be rotated in either direction by means of two gravity-pawls, G G', which, suspended above it, are at 80 times permitted to drop, and thus engage therewith. Thus they become alternately active or inactive, dependent upon the divergence of the endless band. When the latter continues in its proper path of travel, both the pawls are maintained inactive. The lateral and opposite edges of the endless band bear against and 85 wipe two feather-bars, *b b'*, at the time when the felt has diverged and it is desired to change its course of travel. These feather-bars are adjustably secured upon an arm, *c*, which extends across the machine and beneath the felt or endless band. (See Fig. 2.) This arm is connected with a rocking plate, H, pivotally disposed in and surmounting the post *a*. Said plate is furthermore vertically aligned above 95 the toothed wheel, and is constructed with two

oppositely-disposed lateral arms, $d'd'$, which interconnect with the extremities of the pawls, preferably by chains, to permit said pawls to drop readily and engage the toothed wheel 5 upon rocking of the plate H. A counterbalance-weight, I, is also attached to this plate and hangs below its pivot, to render the return of the plate to a normal position more positive, and thus hold and retain both pawls inactive 10 so long as the felt continues in its normal path of movement. These pawls G G', above mentioned, are loosely hung upon a hub, s, securely affixed at the extremity of a shaft, e, preferably rectangular in cross-section, which is located 15 within the sleeve-shaft D and adapted to oscillate in order to actuate the active pawl and shift the position of the toothed wheel. The mechanism for effecting the oscillation of the shaft e is arranged as follows: At the end 20 of the journal f of the guide-roll B is attached a face-plate, g, provided with a crank-rod, J. The lower extremity of the latter is connected with a cross-head, K, sliding in a boss, L, cast on a carriage, M, which is mounted and reciprocates 25 on the shaft D, slotted at t. This carriage carries the adjustable journal of the roll, and is formed with an upper and lower hub and an interconnecting web-piece. The upper hub is slotted at h; while the lower one is adapted to 30 receive a screw-threaded nut, i. The latter is firmly attached to the carriage and engages the screw-shaft E.

As before premised, constant rotation of the guide-roll by means of the endless band C actuates the crank-rod J and cross-head K, which, through interconnecting mechanism, produces continuous rocking of the pawl-carrying shaft e. This mechanism consists of a connecting-rod, N, which is secured at its lower end in a 35 slot, x, formed in the cross-head, while its upper end is attached to the extremity of a lever-arm, j, extending from a hub, P, which is capable of endwise travel thereon with the carriage, as occasion requires. The slots h t, provided, respectively, in the upper hub of the 40 carriage M and the sleeve-shaft D, are to permit reciprocations of the lever-arm j. The slot t performs the further office in permitting endwise travel of the arm j upon the shaft e, as before explained. 45

A safety attachment to control excessive travel endwise of the sliding carriage in either direction is further employed, and consists of a rod, Q, provided with adjustable hubs k k' 50 and supported in the posts a a'. This rod is aligned in the path of travel of the carriage and passes loosely through the latter. Thus when said carriage has advanced to the extreme limit of travel desired it shrugs the rod Q by means of the hubs endwise a short distance. This actuates a rod, R, which is pivotally united with it. The rod R is furthermore swung in a bracket on the post a, and is furnished at each end with lugs m m', having 55 inclined faces which engage similar but oppositely-disposed lugs, n n', on the rear side of

the pawls. Hence, presuming the carriage has been advanced by the rotations of the screw-shaft E until it contacts with the lug k', the rod Q is shrugged endwise in direction of arrow 1, while the lug m is advanced to engage the lug n on the pawl G, which is now raised and rendered inactive. Reverse movement of the carriage to the other extreme similarly thrusts the lug m' against the pawl-lug n', to render the pawl G' inactive. Thus excessive travel of the sliding carriage M in either direction is prevented and injury to the several parts of the apparatus avoided, which would be liable to happen were not means taken to control and render the pawls inactive when desired. 70

The operation of this guide mechanism is as follows: Presuming the endless band is traveling continuously in the course indicated by arrow 3, but trending in the direction of arrow 2 or against the feather-bar b, the continuous rotations of the guide-roll B actuate the crank-rod J by means of the face-plate on its journal f and reciprocate the cross-head, which in turn communicates, by means of the rod N and lever-arm j, oscillating motion to the pawl-shaft e; hence it will be readily observed that the latter is continuously active, while the pawls engage the toothed wheel F only when the endless band bears against one of the feather-bars b b'. 75

In the present instance the bar b is the one employed, and the rod c and rocking plate H are tilted upward, permitting the pawl G' to drop until it rests upon the wheel F. The latter is now advanced in direction of arrow 4, (see Fig. 2,) while the shaft E is rotated. By this latter motion the sleeve-nut i, secured to the carriage M, is compelled to advance in direction of arrow 6, and carries with it the carriage, which slides on the tubular shaft D in conformity with the endwise travel of the nut on its actuating-shaft. This changes the position of the axis of the guide-roll and causes 90 the divergence of the endless band to be reversed. 100

Converse trend of the endless band will produce pressure against the opposite bar, b', depress the bar c, and lower the pawl G, which will now engage the wheel F and reverse the movement of the carriage with the guide-roll journal f. The counterbalance-weight I causes both pawls to be held in a state of idleness as soon as the pressure from the endless band on 105 the feather-bars is removed. 115

When the carriage has reached the extreme point desired in the act of adjusting the guide-roll, the carriage M shrugs the rod Q, and the pawl then active is at once reduced to a state 120 of inactivity, when the carriage is stopped. 125

I claim—

1. The combination, with a continuously-traveling guide-roll provided with a fixed and movable journal, the carriage in which the movable journal is mounted, and the hollow slotted shaft on which said carriage travels, of the 130

pawl-carrying rod within said shaft and continuously oscillated by the guide-roll to shift the latter axially, substantially as set forth.

2. The combination, with a guide-roll and the endless band traveling thereon, of the frame with the hollow fixed slotted shaft and the rotating screw-shaft, said shafts being interconnected by a sliding carriage, which is actuated at intervals of time by the guide-roll, caused by divergence laterally of said band, substantially as stated.

3. In combination with the guide-roll, the crank-rod, cross-head, and lever-arm operated thereby to oscillate the pawl-shaft, the rocking gravity-plate with its feather-bars actively induced by a continuously-traveling band, and the screw-shaft rotated by pawls to move the journal-carriage of the guide-roll, as and for purposes herein described.

4. The endless band C, disposed between the feather-bars b b', the tilting lever c, and the gravity-plate H, actuated by the latter, in combination with the pawls G G', mounted on the continuously-oscillating shaft e and co-operating with the toothed wheel F and screw-shaft E to

move the carriage M and axially shift the guide-roll, substantially as described.

5. In mechanism for controlling the path of travel of an endless belt, the guide-roll B, its journal-carriage M, supporting tubular shaft D, and actuating pawls G G', with lugs n n', combined with the movable rod Q, adapted to be shrugged by the carriage, and the pivotal rod R, with its lugs m m', adapted to engage the pawls singly, as and for purposes herein set forth.

6. The combination, with the slotted sleeve-shaft D, the screw-shaft F, and the carriage M, reciprocating thereon, of the lever-arm j, with its hub P, movable endwise upon the shaft e within the sleeve D, said shaft being connected with and rocked by the guide-roll, its rod J, and cross-head K, substantially as stated.

In testimony whereof I affix my signature in presence of two witnesses.

RICHARD SMITH.
